KICK-OUT FOR METAL WORKING
MACHINESWilliam L. Clouse, Tiffin, Ohio, assignor to The
National Machinery Company, Tiffin, Ohio

Application November 10, 1930, Serial No. 494,787

10 Claims. (Cl. 10—11)

This invention relates to a kick-out for metal-working machines whereby an article shaped in a heading or forging machine can be forced readily from the die recess in which it is held so as to clear the die for the reception of another blank.

The primary object is to provide a kick-out which will start the article gradually to break its intimate contact with the shaping die and thereafter eject it with a rapidly accelerated motion.

Another object is to provide a kick-out having a powerful leverage action whereby the shaped forging can be dislodged from the die recess.

15 With the foregoing and other objects in view which will appear as the description proceeds, the invention resides in the combination and arrangement of parts and in the details of construction hereinafter described and claimed, it 20 being understood that changes in the precise embodiment of the invention herein disclosed may be made within the scope of what is claimed without departing from the spirit of the invention.

25 In the accompanying drawing the preferred form of the invention has been shown. Said drawing is a view partly in section and partly in elevation showing portions of a heading machine equipped with the present improvements.

30 Referring to the drawing by characters of reference, 1 designates a stationary die with which co-operates a movable die 2. The die 1 has a kick-out plunger 3 slidable therein and constituting an abutment for the blank B while being 35 shaped. This plunger bears against the rounded end 4 of a kick-out lever 5 and the said end also bears normally against a stop 6. This stop preferably alines with rod 3 and can be adjustably mounted by screwing it into its support 7 as 40 shown.

45 Lever 5 is fulcrumed between its ends at 8 and one arm thereof is engaged by an elongated rounded cam 9 fulcrumed at 10 and having an arm 11. A rod 12 can connect the arm 11 to an eccentric, or to an arm 13 carried by an operating shaft 14 whereby an eccentric movement or the like will be set up to actuate the rod 12 in properly timed relation with the movable die 2.

Under normal conditions the kick-out mechanism is positioned as shown by full lines in the drawing. A blank B can then be carried to the stationary die where it will abut against plunger 3 during the shaping operation.

55 After die 2 has moved away from the shaped article as shown in the drawing, the shaft 14

can be caused to rock. This will operate the kick-off mechanism. It will be noted that the portion of cam 9 nearest the fulcrum 10 is concentric therewith. The working edge of the cam then curves gradually away from the fulcrum 60 and forms an elongated active surface. Consequently, when rock shaft 14 transmits motion through arm 13 and rod 12 to arm 11 the cam will be shifted quickly from its full-line position to the broken-line position shown. As lever 5 65 constantly bears against the cam and is normally close to the fulcrum 10 the first movement of the cam will result in a very slight movement of the lever but a powerful leverage will be exerted as will be obvious.

70 This slight initial movement will be sufficient to cause lever 5 to press plunger 3 longitudinally a sufficient distance to break the intimate contact of the shaped blank B with the die 1. Thereafter the cam 9 will speed up the movement of the lever 5 and kick-out plunger 3 with the result that the loosened blank will be ejected and the die prepared to receive another blank.

75 The insertion of a new blank can be utilized for returning the kick-out mechanism to its original position or, if preferred, the parts can be returned by a spring or other mechanical means provided for that purpose.

80 Up to the present time manufacturers of rivet and bolt heading machines have overlooked the fact that rapidity of a kicking blow has caused the kicking tool 3 to upset the back end of the rivet shank B so that added wear was thrown upon the die 1 in pushing out the swelled or upset rear end of shank B. Heretofore no cam-operated construction has operated at a speed 85 sufficiently slow to kick out the shank without upsetting or swelling it. As quite a travel has been necessary in order to handle long lengths of work and as there is a limit to the number of degrees of the revolution of the shaft during which the work must be ejected, a cam with a "high hill" has been necessary. As a result of previous efforts at a kicker device, it has been necessary to use an excessive speed in starting and this has tended to upset the end of the work 90 on account of the blow imparted. In the present device the lower end of the lever 5 remains in contact with the concentric portion of the cam portion 9 of the lever 11, and as the lever 11 moves thru its arc, the lever 5 starts from zero speed and moves very slowly, on account of the short lever arm of the contact point of the cam 9, operated with the long lever arm from the contact point to the fulcrum 8 on the lever 5. 95

100 Under normal conditions the kick-out mechanism is positioned as shown by full lines in the drawing. A blank B can then be carried to the stationary die where it will abut against plunger 3 during the shaping operation. 105 After die 2 has moved away from the shaped article as shown in the drawing, the shaft 14

However, after this first slow motion, which pushes the blank B out of the die without upsetting the back end, has been accomplished, then the contact point of the cam 9 raises to a point higher up on the lever 5, with the result that the distance from the fulcrum 10 to the point of contact on the cam 9 rapidly increases, giving a longer lever arm, and at the same time, as the point of contact of the cam 9 approaches the fulcrum 8 of the lever 5, the movement of this lever arm decreases, with the result that there is a high rate of acceleration between the operating lever 11 and the ejecting lever 5. The two cam surfaces cooperating as they do on the levers 11 and 5 make possible an extremely slow movement of the lever 5 during the first part of its stroke, and still enable the blank B to be kicked or ejected from the dies in the necessary length of time on account of the acceleration of the lever 5 at the finishing end of its stroke.

What is claimed is:

1. In a metal-working machine a shaping die, a blank ejecting plunger therein constituting an abutment for a blank in the die, a stop, a kick-out lever having one end normally between and in contact with the plunger and stop for transmitting thrust from one to the other, and means engaging the lever for moving it and the plunger gradually from a standing position to gently dislodge a blank in the die and with rapid acceleration to blank ejecting position, said means including an oscillating cam mounted to work in the same plane with the kick-out lever and having a lever engaging face one end portion of which is concentric with the axis of rotation of the cam and merges into a portion which diverges abruptly from said axis, and means for rocking the cam to advance its point of contact with the lever from said concentric portion along the lever toward the axis of the lever, thereby to shorten the distance between said axis and said point of contact and correspondingly accelerate the movement of the lever.
2. In a metal-working machine a shaping die, a plunger therein for ejecting a blank and constituting an abutment for the blank in the die, a stop, means for transmitting thrust from the plunger to the stop, and mechanism proportioned and positioned to actuate said means to move the plunger gradually from a standing position to gently loosen a blank in the die and with rapid acceleration to blank ejecting position, said mechanism including a lever having one end between the plunger and stop, an elongated cam engaging the other end of the lever and having a working face diverging abruptly from a portion concentric with the axis of rotation of the cam, and means for swinging the cam in the plane of movement of the lever to advance the point of contact between the cam and lever toward the axis of the lever, thereby to accelerate the movement of the lever.

3. In a metal-working machine a shaping die, a blank ejecting plunger therein constituting an abutment for a blank in the die, a stop, a kick-out lever having one end interposed between and transmitting thrust from the plunger to the stop, and mechanism for actuating said lever to move the plunger gradually from a standing position and with rapid acceleration to blank ejecting position, said mechanism including a lever mounted for oscillation having an elongated cam initially engaging one end of the kick-out lever, and said cam having a working face diverging abruptly from a portion concentric

with the axis of rotation of the cam, and means for rocking the cam lever in the plane of movement of the kick-out lever to advance the point of contact between the levers along said concentric portion of the cam and thence along the cam and kick-out lever toward the axis of said kick-out lever to accelerate the movement of the kick-out lever.

4. In a metal working machine a shaping die, a kick-out plunger therein constituting an abutment for a blank being shaped, a kick-out lever having one arm in contact with one end of the plunger, an oscillating lever having a portion concentric with its axis of movement from which is extended an arm having an elongated convex cam-edge merging gradually into said concentric portion, said concentric portion being in contact with the other arm of the kick-out lever, and means for swinging the cam lever toward and in the plane of movement of the kick-out lever, said levers being shaped and relatively mounted to gradually transfer contact with the kick-out lever from the concentric portion to the cam portion of the cam lever during the swinging of the cam lever in one direction, thereby to start the kick-out lever at zero and thereafter transfer thrust thereagainst from the cam portion at points advancing toward the axis of the kick-out lever, thereby to actuate the kick-out lever minutely at first to thrust slowly through the plunger against the blank to loosen the blank without upsetting it, and then rapidly to accelerate the kick-out lever to expel the blank, the levers being proportioned and timed to produce a relatively long stroke of the plunger during a short annular movement of the oscillating lever.

5. In a machine for upsetting metal blanks, a shaping die, and means for ejecting the upset blank from the die without expanding the blank, said means including a kick-out plunger constituting an abutment for the blank, a lever engaging the plunger, and a cam for thrusting against the lever progressively toward the axis of the lever thereby to impart an initial minute movement to the plunger while in contact with the blank to loosen the blank from the die and for subsequently accelerating the movement of the plunger to eject the blank.

6. In a machine for upsetting metal blanks, a shaping die, and means for ejecting the upset blank from the die without expanding the blank, said means including a kick-out plunger constituting an abutment for the blank, and contacting levers one of which engages the plunger, said levers cooperating to advance their point of contact toward the axis of one of the levers thereby to exert maximum leverage at minimum speed to impart an initial minute movement to the plunger while in contact with the blank thereby to loosen the blank in the die without expanding it, and to simultaneously accelerate the stroke of the plunger and proportionately reduce the leverage to eject the loosened blank.

7. In a machine for upsetting metal blanks, a shaping die, and means for ejecting the upset blank from the die without expanding the blank, said means including a kick-out plunger constituting an abutment for the blank, an operating shaft, and a variable driving connection between the shaft and the plunger including a kick-out lever bearing against the plunger, an oscillating lever bearing against and working in the plane of movement of the kick-out lever and having a portion concentric with its axis and an elongated cam portion, and means for actu-

- ating the oscillating lever, said variable drive connection and lever being proportioned and arranged to transfer thrust gradually against the kick-out lever from the concentric portion to the 5 cam portion and along the kick-out lever toward the axis thereof thereby to exert maximum leverage at minimum speed and minutely actuate the plunger to loosen the blank without expanding it, and thereafter exert diminishing leverage at increasing speed to accelerate the stroke of the 10 plunger and eject the blank.
8. In a machine for upsetting metal blanks, a shaping die, and means for ejecting the upset blank from the die without expanding the blank, 15 said means including a kick-out plunger constituting an abutment for the blank, and variable driving means for the plunger including a kick-out lever, one arm of which constitutes an abutment for the plunger, an oscillating lever 20 having a portion concentric with its axis and an elongated arm, and means for actuating the oscillating lever to transfer thrust therefrom progressively along one arm of the kickout lever toward the fulcrum thereof thereby to actuate 25 the kick-out lever initially at minute speed with maximum leverage and subsequently at accelerated speed and proportionately reduced leverage, thereby to initially loosen the blank gently in the die and subsequently eject the blank at high 30 speed.
9. In a machine for upsetting metal blanks, a shaping die, and means for ejecting the upset blank from the die without expanding the blank,

- said means including a kick-out plunger constituting an abutment for the blank, a kick-out lever in contact with one end of the plunger and having an elongated arm, an oscillating lever having a portion concentric with its axis and an arm with an elongated convex surface merging into said concentric portion, said elongated arm being initially in contact adjacent to its free end with the concentric portion and said convex surface constituting means for thrusting against the elongated arm progressively toward the fulcrum of the kick-out lever, thereby to actuate said lever initially at a minimum speed with a maximum leverage to gently shift the plunger and loosen the blank, and thereafter propel the plunger at a rapidly accelerating speed with a leverage reduced in proportion to the increase of speed, to expel the loosened blank.
10. In a metal working machine a plunger for ejecting formed blanks, a lever for thrusting against the plunger, an elongated cam having a concentric portion and an eccentric portion, said cam normally contacting with the lever, and means for actuating the cam to transfer thrust to the lever from the concentric portion and then from the eccentric portion, progressively toward the axis of movement of the lever, thereby to convert the movement of the plunger from standing position into rapidly accelerated sliding movement to gently dislodge a formed blank and quickly eject it.
